UNITED STATES PATENT OFFICE.

WILLIAM P. BETTENDORF, DECEASED, LATE OF BETTENDORF, IOWA, BY JOSEPH W. BETTENDORF, ADMINISTRATOR, OF DAVENPORT, IOWA.

ROOF FOR CARS.

1,026,899.

Specification of Letters Patent.

Patented May 21, 1912.

Original application filed April 8, 1910, Serial No. 554,184. Divided and this application filed August 13, 1910. Serial No. 577,094.

To all whom it may concern:

Be it known that WILLIAM P. BETTENDORF, deceased, late a citizen of the United States, residing at Bettendorf, in the county 5 of Scott and State of Iowa, did invent new and useful Improvements in Roofs for Cars, of which the following is a full, clear, and exact description.

This invention relates to the construction 10 of the roofs of railway cars, and more particularly to cars having "knock-down" bodies, similar to that set forth in an application for patent filed by said William P. Bettendorf, April 8th, 1910, Serial No. 15 554,184, for box car construction (Case 171) of which the present application is a division.

It is the object of said invention to provide a car-body with a roof the parts of 20 which can be quickly assembled or can be readily dismantled or removed for the purpose of loading the car, or converting it from a box to a gondola car, or vice versa, and a further object is to permit of this removal of the roof elements without disturbing the structural independence of the side-walls of the body or without the necessity of loosening nuts or removing bolts. This is accomplished by the means and in the 25 manner hereinafter fully described, and as more particularly pointed out in the claims, reference being had to the accompanying drawings, forming a part hereof, in which,

Figure 1 is a top plan view of one end 30 portion of the improved car-roof. Fig. 2 is a vertical end elevation of the roof showing the side-wall of the car in section and a fragment of the rear-wall. Fig. 3 is a plan view of a fragment of the roof including the 35 union of the roof elements and the ridge support, drawn to an enlarged scale. Fig. 4 is a detail view illustrating the end coupling of a carline. Fig. 5 is a side view of one end of the same. Fig. 6 is a central longitudinal vertical section of one end of the 40 car supporting the improved roof.

The car to which the improvements are 45 adapted to be applied has suitable corner-posts B, B, arising from the corners of its floor, that is supported on a suitable under frame X and is provided with side-walls and end-walls A, A', supported by said posts, substantially as set forth in the afore-said pending application of which this is a

division. The only features of these parts 55 with which the invention involved in this application co-operates are the upper rolled tubular edges c and d of said walls, and the vertical slits made in the inner web of the triangular upper ends of said posts, as will 60 hereinafter more fully appear. The corner posts have their lower ends suitably secured to the floor or underframe, and their upper ends terminate just below the eaves of the roof members, and substantially T-shaped 65 side-posts or stakes B', are located at the center of length of the car, that are secured to and arise from said floor or underframe and are of the same height as said corner-posts. The improved roof of this car-body 70 preferably consists of two rectangular screens 10, each of which is bounded by a suitable channel-iron frame 2, and each of which is of a length corresponding to the distance between the end-walls of the car, 75 and of a width corresponding to the width of one side of the slope of the roof. At this point it may be mentioned that instead of screening, solid plates might be employed for these roof elements; for convenience, 80 however, these elements will hereinafter be referred to as "screens." At the ends of the car, these screens are supported by carlines 14, that arch over from the top of one corner-post to the other. These carlines are 85 arranged in transverse vertical planes just inside the end-walls, and their ends are bent laterally toward the ends of the car and have substantially T-shaped dowels 15, that enter the vertical slits (hereinbefore referred to) in the angular web connecting the outer webs of the top of the corner posts. In order to lock the ridge of said screens together, frames 2, thereof have suitable plates 3 secured to their outer surfaces, which latter are provided with fingers 4 that project in transverse alinement with the ends of frames 2, beyond the adjacent longitudinal edges thereof, a short distance, which fingers are provided with heads 5, having 90 greater vertical dimensions. When the screens are assembled, the heads of these fingers are dropped into depressed seats made in the horizontally projecting members 6 of standards 7, each of said standards, is 95 preferably, Y-shaped in cross section and extends down to and is provided with a concaved foot 8 that rests upon the top of 100 105

the end-walls at the center of width of the car. The plate 3 is also provided with laterally projecting studs 9, the function of which is such that, when said screens are lifted off the top of the car, they catch upon the brackets *e* projecting outward from the outer ends of the end-posts, as hereinbefore stated, and support said screens alongside the upper portions of the sides of the car in the position shown in dotted lines in Fig. 2 of the drawings.

At their lower corners screens, 10, are provided with studs, 12, that are secured in and project outwardly from the marginal frame, 2. When the screens are in their proper positions, these studs enter suitable apertures made to receive the same in the tubular upper edges of the side-walls, and, when said screens are locked by means of a pad-lock engaging the vertical extension 13, that arises from standard 7 between fingers 4, the screens will be locked in position.

What is claimed as new is:—

1. A car-body comprising a suitable underframe, corner-posts, car-lines at each end of said car-body removably secured to and arching from one post to the other, and integral roof members each extending from end to end of said body between the ridge thereof and the eaves of the roof and removably secured upon said car-lines.

2. A car-body comprising an underframe, corner-posts, end-walls secured to said posts, carlines removably secured to and arching from one post to the other, roof members removably supported upon said carlines, and standards resting upon said end-walls the upper ends of which are engaged by said roof elements.

3. A car-body comprising an underframe, corner-posts, end-walls secured to said posts, carlines removably secured to and arching from one post to the other, roof members

removably supported upon said carlines, transverse fingers secured to and projecting from the corners of said roof members and provided with enlarged ends, and standards resting upon said end-walls the upper ends of which are engaged by said fingers.

4. The combination with a car-body, of a roof therefor comprising carlines at each end of said body and secured to and arching from side-wall to side-wall of the same, and integral half roof members one on each side of the ridge of the roof and extending from end to end of the car-body each of which are removably supported by said carlines, between the ridge and eaves of the roof.

5. The combination with a car-body, of a roof therefor comprising carlines secured to and arching from side-wall to side-wall of said body, standards supported by the end-walls intermediate their ends, and integral half roof-members one on each side of the ridge of the roof that are removably supported by said carlines and the upper corners of which rest upon said standards.

6. The combination with a car-body, the upper edges of the walls of which are reinforced, of a roof therefor comprising carlines secured to and arching from side-wall to side-wall of said body, a standard mounted on the upper edge of each end-wall intermediate the ends of the same, and roof members removably supported by said carlines and the upper corners of which rest upon said standards.

In witness whereof I have hereunto set my hand this 5th day of August, 1910.

JOSEPH W. BETTENDORF,
Administrator of the estate of William P.
Bettendorf, deceased.
